(57) **ABSTRACT**

The present invention provides a protective cover for a baby carrier ring and a set thereof. The protective cover is a pocket formed from a pair of washable shields having at least one fastener. The fabric pockets are conformable around baby carrier rings. Each pocket is removably attachable to a baby carrier ring with the fastener. The washable material of the pocket protects the ring from damage while, for example, washing, drying, storing, and shipping the baby carrier.

PROTECTIVE COVERS FOR BABY CARRIER RINGS

CROSS-REFERENCE TO RELATED APPLICATION

This application claims the benefit of priority of U.S. provisional application No. 62/973,122, filed Sep. 18, 2019, the contents of which are herein incorporated by reference.

BACKGROUND OF THE INVENTION

The present invention relates to protective articles for baby carrier rings and, more particularly, to fabric pockets for protection of baby carrier rings.

Many baby carrier manufacturers recommend putting a sock over the baby carrier rings to protect them from damage. Socks do not reliably stay in place, are cumbersome, and cover too much fabric/material on the carrier. Therefore, they do not adequately protect the baby carrier rings. Using socks to protect rings also inhibits the carrier fabric from being thoroughly cleaned when washing.

As can be seen, there is a need for a protective article for baby carrier rings that does not fall off and does not interfere with cleaning the baby carrier fabric.

The present invention provides ring wraps or pockets that attach to the rings of a baby carrier to protect the baby carrier rings from damage. The ring wraps have a fastener to keep them in place on the rings so that ring wraps do not slide off. The ring wraps do not envelope a large amount of material and do not interfere with washing a baby carrier.

SUMMARY OF THE INVENTION

In one aspect of the present invention, a protective cover for a baby carrier ring is provided, comprising a pocket formed from a pair of washable shields having at least one fastener.

In another aspect of the present invention, a protective cover set for baby carrier rings is provided, comprising a plurality of fabric pockets configured to conform around a plurality of baby carrier rings, wherein each of said plurality of fabric pockets is removably attachable to one of the plurality of baby carrier rings with at least one fastener.

These and other features, aspects and advantages of the present invention will become better understood with reference to the following drawings, description, and claims.

BRIEF DESCRIPTION OF THE DRAWINGS

FIG. 1 is a top perspective view of two protective ring covers according to an embodiment of the invention;

FIG. 2 is a front perspective view thereof;

FIG. 3 is a top plan view thereof;

FIG. 4 is a bottom plan view thereof;

FIG. 5 is an enlarged view of the inside thereof; and

FIG. 6 is a perspective view thereof, shown in use with baby carrier rings secured within.

DETAILED DESCRIPTION OF THE INVENTION

The following detailed description is of the best currently contemplated modes of carrying out exemplary embodiments of the invention. The description is not to be taken in a limiting sense but is made merely for the purpose of

2

illustrating the general principles of the invention, since the scope of the invention is best defined by the appended claims.

As used herein, the term "shield" refers to a device or part 5 that serves as a protective cover or barrier.

Broadly, one embodiment of the present invention is a ring cover, comprising a washable material and a fastener, for protecting the rings on baby carriers from damage. The washable material of the cover generally protects the rings 10 from damage while, for example, washing, drying, storing, and shipping, the baby carrier.

In some embodiments, the ring cover may be configured as a protective pocket having at least one fastener. The protective pocket may be installed by sliding it onto a baby 15 carrier ring. In other embodiments, the ring cover may be a ring wrap configured as a toroidal sheath having at least one fastener. The ring wrap may be installed by wrapping it around the ring, leaving the area in the center of the ring open.

20 The materials of manufacture are not particularly limited. The washable material may be selected from a variety of textiles, including but not limited to the group consisting of fleece, fleece adhered to another fabric, other protective materials, and a combination thereof. The fastener may be, for example, selected from the group consisting of snaps, buttons, zippers, and hook-and-loop closures.

25 In an embodiment, the inventive pocket may be manufactured as follows. Fabric may be adhered to fleece with an iron-on adhesive activated by heat from an iron. The fleece and fabric may be cut into shields generally having the shape of a major segment of a circle and hemmed. Snaps or other fasteners may be installed near the center of each component in a manner known to a person skilled in the sewing art. The hemmed components may then be sewn or stitched together 30 around the circumference of the circular portion to form pockets, preferably with the fleece portion on the interior of the pockets.

35 To use the inventive articles, one cover may be fastened in place over each ring on the baby carrier, holding the cover in place. In some embodiments, adjacent pockets may be snapped to one another to protect a plurality of rings.

40 Referring to FIGS. 1 through 6, a pair of protective ring covers 10 according to an embodiment of the invention are shown. Each cover 10 comprises a fabric 20 pocket 60. 45 Iron-on fleece 30 may be fused to the interior surface of the fabric 20 and the fabric 20 may be hemmed with thread 40. Snaps 50 may be installed near the center of each protective ring cover 10. FIG. 6 illustrates use of the inventive covers 10, such that a cover 10 surrounds each baby carrier ring 80 50 of a baby carrier 70.

It should be understood, of course, that the foregoing relates to exemplary embodiments of the invention and that modifications may be made without departing from the spirit and scope of the invention as set forth in the following 55 claims.

What is claimed is:

1. A protective cover for a baby carrier ring, comprising a washable ring cover having an internal fastener, wherein 60 the protective cover is configured in the shape of a major segment of a circle, and wherein the internal fastener is located closer to a center of the protective cover than an edge of the protective cover such that when the baby carrier ring is fully inserted into the protective cover, the internal fastener is located within an opening of the baby carrier ring in order to removably attach the protective cover to the baby carrier ring.

2. The protective cover of claim 1, wherein the washable ring cover comprises fleece adhered to another fabric.
  3. The protective cover of claim 1, wherein the washable ring cover is configured as a sheath.
  4. The protective cover of claim 1, wherein the washable ring cover is configured as a pocket formed from a pair of shields.
  5. The protective cover of claim 4, wherein the pair of shields are stitched together around a circumference of the major segment of a circle to form the pocket.
  6. The protective cover of claim 1, wherein the internal fastener is selected from the group consisting of snaps, buttons, and hook-and-loop closures.
  7. The protective cover of claim 6, wherein the protective cover further comprises an external fastener attachable to an external fastener of an adjacent protective cover.
- 15
8. A protective cover set for baby carrier rings, comprising a plurality of fabric covers configured to conform around a plurality of baby carrier rings, wherein each of said plurality

of fabric covers has an internal fastener, wherein each of said plurality of fabric covers is configured in the shape of a major segment of a circle, and wherein each of the internal fasteners is located closer to a center of a respective fabric cover than an edge of the respective fabric cover such that when the baby carrier rings are fully inserted into the fabric covers, each of the internal fasteners is located within an opening of a baby carrier ring in order to removably attach the fabric covers to the baby carrier rings.

10 9. The protective cover set of claim 8, wherein the plurality of fabric covers are configured as a pocket or as a sheath.

10 10. The protective cover set of claim 8, wherein the plurality of fabric covers are lined with fleece.

15 11. The protective cover set of claim 8, wherein each of said plurality of fabric covers further comprises an external fastener operable to attach adjacent fabric covers.
